PIG AND HOG FEEDER

Abraham S. Friedman, Hicksville, Ohio, assignor to The National Ideal Company, Toledo, Ohio, a corporation of Ohio

Application April 29, 1958, Serial No. 50,665

Term of patent 7 years

(Cl. D12—2)

FIG. 1.

FIG. 2.

Fig. 1 is a perspective front elevation of a pig and hog feeder embodying my design; and

Fig. 2 is a perspective rear elevation thereof.

The undisclosed end of the pig and hog feeder is substantially plain in appearance.

I claim:

The ornamental design for a pig and hog feeder, substantially as shown and described.
